Patented Dec. 10, 1918.

THE MORRIS PETERS CO., PHOENIX, ARIZONA, U.S.A.

UNITED STATES PATENT OFFICE.

ROBERT G. NICHOLAS, OF CLYDE, KANSAS.

TOY GUN.

1,287,401.

Specification of Letters Patent. Patented Dec. 10, 1918.

Application filed December 31, 1917. Serial No. 209,656.

To all whom it may concern:

Be it known that I, ROBERT GRANT NICHOLAS, a citizen of the United States, residing at Clyde, in the county of Cloud, and State 5 of Kansas, have invented certain new and useful Improvements in Toy Guns, of which the following is a specification.

This invention relates to an improved toy gun and has as its primary object to provide 10 a gun of this character especially adapted for shooting an arrow or other similar projectile.

The invention has as a further object to provide a toy gun employing a relatively 15 strong projecting spring so that the arrow will be projected from the gun with considerable force and wherein a very simple trigger construction will be provided for releasing said spring.

20 A still further object of the invention is to provide a toy gun wherein the stock, barrel and body of the gun will all be formed from a single piece of material and wherein the arrow receiving groove in the barrel will be 25 closed upon its upper side by a suitable closure strip completing the contour of the barrel and also providing a guard for the free portion of the projecting spring.

And the invention has as a still further object 30 to provide a toy gun employing a projecting spring of the contractile type and wherein a very simple construction will be provided for retaining the spring stretched to cock the gun.

35 Other and incidental objects will appear as the description proceeds, and in the drawings wherein I have illustrated the preferred embodiment of the invention, and wherein similar reference characters designate corresponding parts throughout the several 40 views:

Figure 1 is a perspective view of my improved toy gun showing the gun cocked and illustrating the arrow employed, in position 45 in the gun barrel,

Fig. 2 is a plan view of the gun with the closure strip for the gun barrel removed,

Fig. 3 is a sectional view taken on the line 3—3 of Fig. 1, more particularly illustrating 50 the manner in which the gun barrel is formed with a groove for receiving the arrow,

Fig. 4 is a fragmentary side elevation particularly illustrating the mounting of the trigger of the gun,

55 Fig. 5 is a similar view showing the shoulder employed upon the stock of the

gun for retaining the projecting spring stretched, and

Fig. 6 is a detailed view of the arrow with its tip.

In carrying out my invention my improved toy gun is formed with a stock 10 at one extremity of which is provided a butt 11 while an upstanding barrel 12 extends longitudinally from the opposite extremity of the 65 stock. As clearly shown in Fig. 1 of the drawings, the stock 10, butt 11 and the barrel 12 are preferably formed integral from a single piece of material and may be constructed of wood or any other approved substance. 70 The barrel 12 is formed with a longitudinally extending slot 13 opening through the upper side of the barrel and at its inner extremity provides a stop shoulder 14. From the said shoulder the upper edge of the stock is cut 75 away longitudinally to form a springway 15 and at the inner end of said springway is further cut away to provide a spring retaining shoulder 16. As clearly shown in Fig. 5 of the drawings, this shoulder 16 80 curves from side to side of the stock and is preferably undercut slightly. Pivoted upon one side of the stock in the rear of the shoulder 16 is a trigger 17, the forward end of which is adapted to move across the 85 shoulder 16 vertically thereof. This trigger lies flat against the adjacent side face of the stock and the rear extremity thereof projects along the butt 11 of the gun so that the trigger may be easily operated. 90

Closing the upper side of the groove 13 in the barrel 12 is a strip 18 which is formed to complete the contour of the barrel. This strip is secured to the upper side of the barrel by nails or other suitable fastening devices and at its inner extremity projects over the springway 15 of the stock to provide, as will presently appear, a guard for the free portion of the projecting spring employed. Supporting the inner end of the 100 said strip is a post 19 arranged immediately in the rear of the spring retaining shoulder 16. This post may be formed integrally with the stock, or, if desired, may be constructed from a block suitably secured to the 105 stock and having the inner end of the strip 18 fastened thereto. Mounted to move within the springway is a projecting spring 20 the intermediate portion of which extends beneath the guard formed by the strip 18 110 to be retained by the said guard. This spring is of the contractile type and the ex-

tremities thereof are secured to opposite sides of the stock by staples or other suitable fastening devices 21. Normally this spring will contract to engage at its intermediate portion with the stop shoulder 14 of the barrel. However, by grasping the intermediate portion of the spring, the said spring may be stretched and consequently shifted rearwardly within the springway 15, to engage, 10 as shown in Figs. 1 and 2 of the drawings, over the shoulder 16, which will then act to retain the spring, when the gun will be cocked. In this connection, it will be noted that the slight undercut of the shoulder 16 15 will tend to prevent accidental displacement of the spring. Furthermore, it will be noted that the post 19 will provide a stop shoulder in the rear of the shoulder 16 so that when stretching the spring 20 to cock the gun, the 20 intermediate portion of the spring may be simply moved to abut the said post in the rear of the spring retaining shoulder and then released, when the spring will immediately shift forward to engage the shoulder 25 16. In order to prevent undue outward force being exerted against the post 19, when thus stretching the spring 20 to cock the gun, a protecting rod 22 is inserted through the strip 18 in front of the said post and embedded in the stock. This rod 22 will thus 30 also serve to reinforce the connection between the said strip and the post.

While any suitable type of projectile may be employed in connection with the gun of 35 the present invention still, as previously intimated, the present toy is particularly designed for shooting an arrow. The arrow employed is, as shown in detail in Fig. 6 of the drawings, formed with a relatively long 40 cylindrical shank 23 equipped at one end with an arrow head 24 and preferably said arrow head is tipped with a rubber or other suitable cushion tip 25 secured to the arrow head in any approved manner.

45 As will now be seen, the shank 23 of the arrow may be inserted through the slot 13 of the gun barrel to project, as shown in Fig. 1, into the springway 15, the projecting spring 20 being in engagement with the retaining shoulder 16 therefor. The gun is then ready to shoot. Aim may be taken in the usual manner, when by depressing the rear extremity of the trigger 17, the forward extremity thereof will be caused to engage 50 the intermediate portion of the projecting spring, as shown in Fig. 4, for lifting the said spring out of engagement with the shoulder 16. The spring may thus be readily released when the intermediate portion 55 thereof will be immediately contracted through the springway to strike the inner end of the arrow shank and project the arrow from the gun. Owing to the length of the said spring it will be seen that the arrow 60 will be so projected with considerable force. 65

It will, therefore, be seen that I have provided a simple toy and one which for this reason will not be likely to get out of order. Furthermore, the toy may be manufactured at minimum cost and owing to its capability 70 of forcibly shooting the arrow or projectile of the gun, will be found a particularly desirable toy of this type.

Having thus described the invention, what is claimed as new is:

75 1. A toy gun including a stock, a grooved barrel carried thereby, a strip connected to the barrel and closing said groove, the said strip projecting at the inner extremity of the barrel to provide a guard member, and a resilient projecting member connected with the stock and having its intermediate portion adapted for movement beneath said guard member toward the outer end of the barrel for expelling a projectile within the 80 barrel.

2. A toy gun including a stock, a grooved barrel carried thereby, the stock being formed with a clearanceway, a strip connected with the barrel to close said groove 90 and projecting over the clearanceway to provide a guard, and a resilient projecting member connected with the stock and having its intermediate portion adapted for movement within the clearanceway beneath 95 said guard toward the outer end of the barrel for expelling a projectile within the barrel.

3. A toy gun including a stock, a barrel carried thereby, a resilient projecting member connected to opposite sides of the stock and having its intermediate portion extending across the inner end of the barrel, means formed on the stock for retaining the intermediate portion of the said member stretched 100 away from the outer end of the barrel, and means mounted upon the stock for releasing said intermediate portion of the member for movement toward the outer end of the barrel to expel a projectile within the barrel. 110

4. A toy gun including a stock, a barrel carried thereby, a resilient projecting member connected to opposite sides of the stock and having its intermediate portion extending across the inner end of the barrel, a shoulder formed on the stock and adapted to retain the intermediate portion of the said member stretched away from the outer end of the barrel, and means mounted upon the stock for releasing the intermediate portion of the member from engagement with the said shoulder for movement toward the outer end of the barrel to expel a projectile within the barrel. 115

5. A toy gun including a stock, a barrel 125 carried thereby, a resilient projecting member connected to opposite sides of the stock and having its intermediate portion extending across the inner end of the barrel, a shoulder carried by the stock and adapted 130

to retain the intermediate portion of the said member stretched away from the outer end of the barrel, and a trigger pivoted upon the stock and having its forward end adapted for engagement with the intermediate portion of the member for releasing the said member from engagement with the shoulder for movement toward the outer end of the barrel to expel a projectile within the barrel.

10 6. A toy gun including a stock, a barrel carried thereby, a strip connected to the barrel and projecting at the inner extremity thereof to provide a guard member, a resilient projecting member connected with the stock and having its intermediate portion adapted for movement beneath said guard member toward the outer end of the barrel for expelling a projectile within the barrel, and means rising from the stock to support the inner end of said guard member and providing a stop adapted to limit the intermediate portion of the said member in its movement away from the barrel.

20 7. A toy gun including a stock, a barrel carried thereby, the stock being cut away at the inner end of the barrel to form a clearanceway and being further cut away at the

inner end of said clearanceway to provide a shoulder, a resilient projecting member connected with the stock and having its intermediate portion adapted for movement within the clearanceway to engage said shoulder for holding the intermediate portion of said member stretched away from the barrel, and means upon the stock for lifting the said member out of engagement with said shoulder to expel a projectile within the barrel.

25 8. A toy gun including a stock, a barrel carried thereby, a shoulder formed from the stock, a resilient projecting member connected with the stock and having its intermediate portion adapted for engagement around the said shoulder for holding the intermediate portion of the member stretched away from the barrel, and means connected with the stock and adapted for engagement with the said member for lifting the intermediate portion thereof out of engagement with the shoulder for movement toward the outer end of the barrel to expel a projectile 50 therein.

In testimony whereof I affix my signature.

ROBERT G. NICHOLAS. [L.S.]
